TO EDWARD H. DEWEY AND FIVE ONE-HUNDREDTHS TO LAURA E. McDERMOTT,
BOTH OF NAMPA, IDAHO.

ROTARY ENGINE.

1,229,179.

Specification of Letters Patent. Patented June 5, 1917.

Application filed December 12, 1916. Serial No. 133,512.

To all whom it may concern:

Be it known that I, ALVAH JEWEL HOWD, a citizen of the United States, residing at Nampa, in the county of Canyon and State 5 of Idaho, have invented certain new and useful Improvements in Rotary Engines, of which the following is a specification.

This invention relates to rotary engines and more particularly to rotary gas engines, 10 although it is to be understood that without material modification, various features of the invention are equally applicable to rotary engines having other motive power means such as steam or compressed air. 15 With this understanding and for convenience of illustration, the invention will hereinafter be described as being applied to a rotary gas engine.

One of the objects of the present invention 20 is to provide a rotary engine adapted to produce a relatively high velocity of the driven member accompanied by high power. Another object is to provide a gas engine of the above character which will be reliable 25 and efficient in use and operation. A further object is to provide a high speed high power gas engine particularly adapted for aeroplanes, autos, etc., which will be compact and self-contained in construction and 30 inexpensive to manufacture.

Other objects will be in part obvious from the annexed drawings and in part indicated in connection therewith by the following analysis of this invention.

35 This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and 45 relation contemplated by this invention, drawings depicting a preferred form have been annexed as a part of this disclosure and in such drawings like characters of reference denote corresponding parts throughout all the views, of which—

Figure 1 is a longitudinal view of such parts of the complete engine as are necessary to fully understand the present invention;

Fig. 2 is a disassembled perspective view 55 of the rotor and its surrounding ring;

Fig. 3 is a detail perspective view of one of the piston elements carried by the rotor;

Figs. 4 and 5 are opposite elevational views of the plates coating with the rotor in which the several explosive chambers or 60 cylinders are formed;

Fig. 6 is a sectional elevational view of a compressor taken on the line 6—6 of Fig. 1;

Figs. 7, 8 and 9 are detail perspective views of certain parts of the compressor as 65 shown in Fig. 1.

Referring now to the drawings in detail and more particularly to Fig. 1, 10 denotes an engine casing preferably of general cylindrical shape having longitudinally mounted 70 therein a shaft 11, carrying a driven member such as a propeller 12 at one end while the opposite end may be provided with cranking or self-starting means, not herein shown.

75 Mounted upon the shaft 11 is a rotor 13 carrying the piston elements 14, the blades of which coat with a series of cavities or cylinders formed in concave plates 16 and 17 adjacent the rotor, as shown more clearly 80 in Figs. 4 and 5, thereby forming a series of cylinders in each one of which an explosion is adapted to take place by means of spark plugs 18 at certain predetermined times. A compressor 20 communicates with 85 the several cylinders by means of one or more passages 21 and is also in communication with a carbureter 22.

90 Before going into the details of construction, it may be stated that air is drawn in with gasolene through the carbureter 22 by the compressor 20 from which it is pumped through the pipe 21 to the several cylinders in the plates adjacent the rotor. The explosive mixture being under compression 95 will be ignited by the spark plugs causing a rotation of the rotor as well as the piston blades rotatably mounted therein. A series of explosions will take place as the rotor 13 turns, thus causing the propeller 12 to be 100 driven at high speed and with great power.

Taking up the details of construction and more particularly the rotor and associated parts, it is to be noted that the disk or rotor 13 as shown more clearly in Fig. 2, comprises a substantially solid relatively flat cylindrical member mounted upon the shaft 11 in fixed position as by means of a key 25. At a plurality of points about the periphery of the disk, in the present case four, are 105 230

22 mounted the piston members 14, Fig. 3. Each member comprises a central hub mounted upon a shaft 26 forced into the rotor 13 through an opening 27 and held in 5 fixed position by means of a counter sunk set screw 28. This central member or hub is provided with a plurality, preferably four, pistons 30. Each piston is, of course provided with suitable packing rings 31 and 10 preferably has its axis inclined at a slight angle to the axis of the shaft 26 in order that it may better coat with the explosive chamber or cylinder formed in the adjacent sides of the plates 16 and 17. It is also to be noted 15 that the rotor is provided with a plurality of properly positioned ports 32 through which the explosive mixture from the pipe 21 is adapted to pass intermittently to the cylinders formed in the plate 16 in desired 20 sequence.

About the rotor and between the plates 16 and 17 is mounted a spark plug ring 35. This ring has its inner periphery substantially equal to the outer periphery of the 25 rotor 13, yet is of a size sufficient to permit free rotation of the rotor therein without undue friction. A series of spark plugs are mounted in this ring 35 and adjacent each spark plug is a passageway 37 communicating with explosion chambers or 30 cylinders directly opposite each other in the plates 16 and 17. Intermediate the spark plugs are openings 38 through which bolts 40 are adapted to pass to clamp the plates 35 16 and 17 tightly against the ring 35 in operative relation to the rotor. At suitable intervals are a third series of openings 41 connecting an exhaust passage 42 in the plate 16 with an exhaust passage 43 in the plate 17. The latter connects with a muffler 43' permitting a discharge of the exhaust gases to a point exterior of the casing. The space between the concave plates and rotor shown in Fig. 1 may be used as a reservoir 45 for lubricant to be distributed to the pistons in any desired manner.

Taking up now the construction of the plates adjacent the rotor as shown in Figs. 4 and 5, each plate is provided with a series 50 of cylinders 45 in which the pistons are adapted to successively coat. These cylinders conform as nearly as possible to the path of travel taken by the cylindrical pistons 30, as they rotate about the main shaft 55 11 and simultaneously about their individual shafts 26. Accordingly, each cylinder 45 is of sufficient width at each end to permit the entrance and exit of the piston as it worms its way about, while at the intermediate part, the opening is much narrower and adapted to take over the inner sides of the piston, so that the piston is substantially buried within the plate at the time the explosion takes place.

60 65 The inner end of each of the cylinders

45, shown in Fig. 4, is connected by means of a port or passageway 46 to the surface of the plate to register with the ports 32 in the rotor.

The opposite ends of each of the cylinders 45 is provided with an exit port 50 communicating with the annular channel 42. There is also a third series of passageways 51 leading from a point slightly within a circle drawn through the central part 75 of each chamber toward the outer periphery of the plate 16, thence through the ports 37 in the casing ring 35 to corresponding ports 52 in the plate 17, shown in Fig. 5. These ports enter the upper ends of the cylinders 45 in plate 17 which are substantially the same in construction as those shown in Fig. 4, while the inner ends of each of these cylinders 45 is provided with 80 an exhaust port 53 communicating with the main annular exhaust ring 43, shown in Fig. 1.

Thus when the parts are in the position shown in Fig. 1 the inner ends of four of the cylinders 45 in the plate 16 and the outer 90 ends of the corresponding four channels in the plate 17 are in communication with each other through the passageway or ports 37 in the ring 35, Fig. 2. At this moment, a spark is produced in the respective four cylinders which causes the rotor to move in the direction indicated by the arrow in Figs. 1 95 and 2. This movement automatically rotates the piston elements 14 in the direction indicated by arrows in Fig. 2, that is one of the pistons moves relatively outwardly into the cylinder 45 in the plate 16 and while the diametrically opposite piston of the same element moves relatively inwardly in the corresponding cylinder 45 of the plate 100 17. It is, of course desirable that the explosion take place when the respective pistons are substantially midway in their respective cylinders.

The impulse obtained by the explosion 110 when the parts are in the position immediately above described causes the compound rotation of each piston unit. Assuming the pistons *a* and *c*, Fig. 3, as having been acted upon, the pistons *b* and *d* are 115 rotated in a clockwise direction, as shown at the top of Fig. 1, bringing the piston *b* into the next adjacent left cylinder 45, shown in Fig. 5, while the piston *d* enters the next adjacent right cylinder 45 in Fig. 120 4. When these pistons *b* and *d* reach mid position in the respective cylinders, the next explosion takes place and the operation is repeated. Thus as the pistons acted upon are forced out of their respective cylinders the following pistons are entering the next adjacent cylinders to repeat the operation. In this way a very rapid series 125 of explosions take place, forcing the rotor about the casing at a high rate of speed and 130

due to the leverage obtained by placing the pistons at the outer periphery of the rotor a high horse power is developed.

At the left of the rotor as shown in Fig. 1 is positioned a magneto 55 having coils and magnets 56 and commutator 57 so positioned and arranged and timed with relation to the rotor as to actuate the desired spark plugs in proper timed relation with the rotation of the parts. As this will form the subject of a separate invention, it is believed to be unnecessary to go into the details of construction at this time.

The compressor 20 shown at the right of Fig. 1 for forcing the explosive mixture to the cylinders comprises a cylindrical casing 60 having a reciprocating piston 61 therein adapted to take in the explosive mixture from the carburetor 22 admitted to passage-way 62 through valves 63 and force the compressed mixture out through valves 64 to the interior of the casing 10. This mixture then passes through the pipe 21 to the cylinders. The reciprocation of the piston 61 keyed or splined to the casing at 59 is obtained by the rotation of the shaft 11 which is provided with right and left-hand threads 65 and 66 respectively. Rings 67 and 68, as shown in Fig. 9, are mounted upon the shaft 11 and are provided with lugs 70 coacting respectively with the threads 65 and 66. These rings are provided on their outer cylindrical surfaces with grooves 71 adapted to be engaged by a lug 72 carried by a flange in a reciprocatory sleeve 73 upon which the piston 61 is mounted. The sleeve 73 is provided with packing rings 74 at each end closely fitting the shaft 11 and the interior thereof may be packed with lubricant as desired. Packing rings 75 are also provided between the casing 60 and the sleeve 73 in order to make the compressor as near air tight as possible.

As to the operation of this device, assume the parts to be in the position as shown in Fig. 1 with the piston having almost completed its left-hand movement. The lug 70 on the ring 67 will have reached the end of its groove and further rotation being temporarily prevented the piston with its lug 72 will be rotated from the ring 68, to the ring 67, thus connecting the piston and ring 67, whereupon further rotation of the shaft 11 will cause the lug 70 on the ring 67 to follow its thread 66 and the piston to the right-hand end of the chamber 60, whereupon the reverse takes place at the right end and the piston 61 once more moves toward the left compressing the explosive mixture in front of it and forcing it out through the left-hand valve 64. Relief ports 76 may be provided as indicated in Fig. 1 to avoid excessive pressure. This mechanism is substantially identical to the internal mechanism of the well known "Yankee screw driver," in

which a continuous movement of the driven element is obtained as the handle is reciprocated.

From the above, it is believed that the construction and operation of the engine will be clear and repetition thereof unnecessary. The device is relatively simple, compact and durable in construction, and is adapted to produce highly satisfactory results in all cases where high speed high power motors are desired.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims:

Having thus described my invention what I claim as new and desire to secure by Letters Patent is:

1. In a rotary engine, in combination, a casing having a plurality of separated cylinders formed in opposite walls thereof, a rotor turning therebetween, and revoluble pistons carried by said rotor successively engaging said cylinders, said pistons being mounted on fixed axes lying in the plane of the rotor.

2. In a rotary engine, in combination, a casing having oppositely disposed plates each having a series of cylinders, a rotor revolvably mounted therebetween and revolvably mounted pistons on fixed axes carried by the rotor coacting with said cylinders.

3. In a rotary engine, in combination, a casing having a plurality of plates each having a series of cylinders, a rotor and a plurality of piston members carried by said rotor and revoluble in a plane at right angles to the plane of the rotor.

4. In a rotary engine, in combination, a casing having two spaced plates, a series of separated cylinders in said plates, a rotor revolvably mounted between the plates and a plurality of revoluble piston members each having a plurality of pistons carried by the rotor engaging the cylinders in the said plates, said pistons being mounted on fixed axes lying in the plane of the rotor.

5. In a rotary engine, in combination, a casing having a driven shaft, a rotor keyed to said shaft, a pair of spaced plates at opposite sides of said rotor normally held in fixed position, a series of separated cylinders in said plates adjacent the rotor, and piston members mounted on fixed axes carried by the rotor coacting with said cylinders first on one side and then on the other.

6. In a rotary engine, in combination, a

casing having a driven shaft, a rotor keyed to said shaft, a pair of spaced plates at opposite sides of said rotor normally held in fixed position, a series of separated cylinders in said plates adjacent the rotor, and piston members carried by the rotor coacting with said cylinders, said piston members comprising a plurality of pistons adapted to successively engage with the series of cylinders and rotating in a plane at right angles to the plane of the rotor about fixed axes.

7. In a rotary engine, in combination, a driven shaft, a rotor keyed thereto, a pair of spaced plates adjacent the rotor, a series of cylinders in said plates, a ring surrounding said rotor and connecting the plates, passage ways from the cylinders of one plate through said ring to the cylinders of the other, spark plugs in said passage ways, and piston members carried by the rotor engaging opposite cylinders.

8. In a rotary engine, in combination, a driven shaft, a rotor keyed thereto, a pair of spaced plates adjacent the rotor, a series of cylinders in said plates, a ring surrounding said rotor and connecting the plates, passage ways from the cylinders of one plate to the cylinders of the other, spark plugs in said passage ways, and piston members carried by the rotor engaging opposite cylinders, said piston members comprising a plurality of diametrically oppositely disposed pistons revoluble about an axis lying in the plane of the rotor.

9. In a rotary engine, in combination, a driven shaft, a rotor keyed thereto, a pair of spaced plates adjacent the rotor, a series of cylinders in said plates, a ring surrounding said rotor and connecting the plates, passage ways from the cylinders of one plate to the cylinders of the other, spark plugs in said passage ways, piston members carried by the rotor comprising a plurality of diametrically oppositely disposed pistons revoluble about an axis in the plane of the rotor, and a magneto controlled by the rotation of said driven shaft.

10. In a rotary engine, in combination, a driven shaft, a rotor keyed thereto, a pair of spaced plates at opposite sides of said rotor, cylinders in said plates, a source of explosive mixture and ports in said rotor controlling the flow of said explosive mixture to said cylinders.

11. In a rotary engine, in combination, a driven shaft, a rotor thereon, a plate adjacent said rotor having cylinders, piston members carried by the rotor coacting with said cylinders, a source of explosive mixture, and ports in the rotor adapted to permit the flow of explosive mixture to said cylinders.

12. In a rotary engine, in combination, a driven shaft, a rotor carried thereby,

revolvably mounted pistons carried by the rotor revolvable in a plane at right angles to the plane of the rotor, a plate having a series of cylinders adjacent the rotor with which the pistons are adapted to coact, and a source of compressed explosive mixture, said rotor having a series of ports corresponding to the series of cylinders adapted to permit a flow of the explosive mixture from its source to said cylinders.

13. In a rotary engine, in combination, a driven shaft, a pair of spaced plates, a series of reversely arranged cylinders in each of said plates, a rotor between the plates and a plurality of piston members each having a plurality of pistons revolvably mounted on said rotor adapted to turn in a plane at right angles to the plane of the rotor and successively coact with said series of cylinders, said rotor having a plurality of ports corresponding to the series of cylinders, and a source of explosive mixture communicating with the cylinders, the flow of said mixture being controlled by the ports in said rotor.

14. In a rotary engine, in combination, a driven shaft, a pair of spaced plates, a series of reversely arranged cylinders in each of said plates, a rotor between the plates, a plurality of piston members each having a plurality of pistons revolvably mounted on said rotor adapted to turn in a plane at right angles to the plane of the rotor and successively coact with said series of cylinders, said rotor having a plurality of ports corresponding to the series of cylinders, a source of explosive mixture communicating with the cylinders, and a ring surrounding said rotor and clamped between said plates having passages therein whereby opposite cylinders are placed in communication with each other.

15. In a rotary engine, in combination, a driven shaft, a pair of spaced plates, a series of cylinders in each of said plates, a rotor between the plates, a plurality of piston members each having a plurality of pistons revolvably mounted on said rotor adapted to turn in a plane at right angles to the plane of the rotor and successively coact with said series of cylinders, said rotor having a plurality of ports corresponding to the series of cylinders, a source of explosive mixture communicating with the cylinders, the flow of said mixture being controlled by the ports in said rotor, a member having passages therein whereby opposite cylinders are placed in communication with each other, and spark plugs in said passages whereby explosions take place simultaneously in opposite cylinders.

16. In a rotary engine, in combination, a driven shaft, a pair of spaced plates, a series of cylinders in each of said plates, a rotor between the plates, a plurality of piston members each having a plurality of pistons

- revolvably mounted on said rotor adapted to turn in a plane at right angles to the plane of the rotor and successively coat with said series of cylinders, said rotor having a plurality of ports corresponding to the series of cylinders, a source of explosive mixture communicating with the cylinders, a ring surrounding said rotor and clamped between said plates having passages therein whereby opposite cylinders are placed in communication, spark plugs in said passages whereby explosions take place simultaneously in opposite cylinders, and a magneto on said driven shaft connected with said spark plugs.
17. In a rotary engine, in combination, a pair of spaced plates each having a series of cylinders provided with inlets and outlets, a rotor between said plates having a plurality of piston members coacting with said series of cylinders, a single spark plug for each pair of cylinders, a magneto on a driven shaft controlling said spark plugs, and a compressor connected by said driven shaft for supplying explosive mixture to said cylinders.
18. In a rotary engine, in combination, a pair of spaced plates each having a series of cylinders provided with inlets and outlets, a rotor between said plates having a plurality of piston members coacting with said series of cylinders, spark plugs for said cylinders, a magneto on a driven shaft controlling said spark plugs, a double acting compressor, and a storage tank in communication with said compressor from which explosive mixture is supplied to said cylinders.
19. In a rotary engine, in combination, a casing having a closed chamber at one end thereof and an open chamber at the other, a compressor in said closed chamber, a carbureter in communication with said compressor, a pair of plates each having a series of cylinders, a rotor between said plates having a plurality of pistons adapted to successively coat with said cylinders, each of said cylinders having an inlet and outlet passage intermittently communicating with said source of explosive mixture, spark plugs for said cylinders, and a magneto on the driven shaft for actuating said spark plugs in timed relation with the rotation of said rotor.

In testimony whereof I affix my signature in presence of two witnesses.

ALVAH JEWEL HOWD.
